UNITED STATES PATENT OFFICE

150,291

DESIGN FOR A WORK HOLDER

Kurt P. Friese, Norwalk, Conn.

Application December 29, 1945, Serial No. 125,186

Term of patent 7 years

(Cl. D54—14)

To all whom it may concern:

Be it known that I, Kurt P. Friese, a citizen of the United States, residing at Norwalk, county of Fairfield, and State of Connecticut, have invented a new, original, and ornamental Design for a Work Holder, of which the following is a specification, reference being had to the accompanying drawing, forming part thereof.

Figure 1 is a perspective view of a work holder, showing my new design.

Figure 2 is a rear view thereof.

I claim:

The ornamental design for a work holder, as shown.

KURT P. FRIESE.
